TWISTED WIRE CONCRETE FORM TIE

Robert C. Gates, Lakewood, Colo., assignor to
Gates & Sons, Inc., Denver, Colo.

Filed Dec. 27, 1971, Ser. No. 112,000

Term of patent 14 years

Int. Cl. D8—08

U.S. Cl. D8—228

FIG. 1.

FIG. 2.

FIG. 3.

FIG. 4.

FIG. 1 is a front elevation view of a twisted wire concrete form tie;

FIG. 2 is a bottom plan view thereof;

FIG. 3 is a top plan view thereof; and

FIG. 4 is an end view thereof.

The rear elevation is identical to the front elevation and the view of the other end is identical to the end shown.

I claim:

The ornamental design for a twisted wire concrete form tie, as shown and described.
